LOOSE LEAF BINDER

Paul O. Unger, Glen Ellyn, Ill., assignor to Wilson-Jones Company, Chicago, Ill., a corporation of Massachusetts

Application October 23, 1933, Serial No. 694,755

9 Claims. (Cl. 129—23)

This invention relates to a loose leaf binder having a headed binding post and particularly to means for securing the top cover member to the binding members.

It is an object of this invention to provide means automatically actuated upon engagement of the binding members with the top cover member to lock the two together. It is a further object of this invention to provide means for preventing separation of said top cover member from the binding members when the binding members are held tightly against the contents of the binder. It is a further object of this invention to provide a rigid binding post having a sheet holding portion of uniform cross sectional area that may be expanded and still maintain the uniform cross sectional area of the sheet holding portion. Other objects of this invention will become apparent upon reading the following description taken in conjunction with the accompanying drawings in which:

Figure 1 is a perspective view of one embodiment of my invention with parts broken away to facilitate illustration of the various structural features;

Figure 2 is a fragmentary perspective view of the top cover member showing the parts held in open position;

Figure 3 is a fragmentary longitudinal sectional view of the top clamping mechanism; and

Figure 4 is a view, similar to Figure 1, illustrating another embodiment of my invention.

Referring to the drawings, Figure 1 shows a lower cover member which includes a cover 2 and a tubular clamping member 3 hingedly connected thereto in any suitable manner. The opposite ends of the tubular clamping member 3 are closed by means of a pair of end caps 4 and 5. The end cap 5 is provided with an aperture 6 to allow access to one end 7 of a right and left hand threaded screw 8 which has a pair of nuts 9 threaded thereon. Each nut 9 has one end of a flexible binding member 10 secured thereto. As shown in Figure 1, the flexible binding member is preferably a conventional chain post such as that disclosed in my prior Patent No. 1,883,253 granted October 18, 1932.

The free end of the flexible binding member 10 is adapted to be protruded through an aperture 11 in the top wall of the tubular clamping member 3 by manipulation of the screw 8 to present a length of chain substantially equal to the height of the stack of sheets 12 to be contained in the binder. The free end of the flexible binding member 10 has secured thereto a

section 13 provided with a head 14 and a restricted neck portion 15. The section 13 may also be provided with a flange 16, as shown in Figure 3, to facilitate compression of the sheets 12, if desired, but the presence of the flange 16 is not essential to the attainment of the advantages of the invention. The section 13 may be threaded into the free end of the binding member 10 so that it is possible to screw a plurality of extension post sections (not shown), of conventional design, to the binding member and then screw the section 13 to the outermost extension post section to provide a binder of greater capacity than the regular length of chain alone will permit.

The binder has a top cover member which includes a cover 17 and a top tubular clamping member 18 hingedly connected thereto. The ends of the tubular clamping member 18 are closed by means of end caps 19. The bottom wall of the member 18 is provided with a pair of circular apertures 20 (Figure 3) large enough to receive the heads 14 of the sections 13 of the binding members 10. The top clamping member is provided with an elongated aperture 21 in its top wall for a purpose hereinafter described. When the clamping member 18 is covered with leather, fabric or similar material, it is preferable to provide a flanged metallic eyelet 22 to protect the edges of the covering material adjacent the aperture 21 and to give the clamping member 18 a finished appearance.

A slide 23 is positioned within the tubular clamping member 18. The slide is slightly shorter than the clamping member to allow for a limited longitudinal movement of the slide. A plurality of flanges 24 of substantially the same height and width as the inside height and width of the tubular clamping member 18 prevents any vertical or lateral movement of the slide. A button 25 is affixed to the slide 23 in registration with the aperture 21 to facilitate longitudinal movement of the slide. Although any suitable type of button may be used, I prefer a non-protruding button because then the binder may be handled on a highly polished surface without danger of marring the finish. The button 25 is preferably provided with a recess 26 that may be engaged by a pencil or similar article to move the slide. If desired, one end of the key (not shown) used to manipulate the screw 8 may be inserted in the aperture 26 to move the slide 23.

The slide 23 is provided with a pair of key-hole shaped apertures 27, the large portions of which are adapted to register with the apertures

- 20 when the slide 23 is in open position. When the slide is moved to closed position the restricted portion of the aperture 27 engages the restricted neck portion 15 of the member 13 to prevent vertical movement of the top clamping member 18 relative to the head of the binding member 10. The slide 23 is provided with a pair of upstanding flanges 28 positioned adjacent the open end of the restricted portion of each of the apertures 27. The flanges 28 are adapted to lie between the head 14 of the binding member and the large portion of the aperture 27, so that when the binding member 10 is tightened against the contents of the binder, the head 14 cannot clear the top of the flanges 28 and longitudinal movement of the slide is absolutely prevented. When the binding members are loosened the heads 14 are able to pass over the flanges 28 so that the top cover member may be removed.
- 20 In chain post binders such as described in my prior patent hereinabove referred to, it has been necessary to turn a key operated screw to operate the slide in the top clamping member. Accordingly, when it is desired to provide means to lock the binder against unauthorized manipulation, as disclosed in U. S. Letters Patent No. 816,915 issued April 3, 1906 to William G. Jones, two separate locks have been required. With my improved construction, a single lock protecting the end 7 of the screw 8 is sufficient to prevent loosening of the flexible binding members or removal of the top cover member.
- 35 The slide 23 is provided with an aperture 29 and an integral pilot arm 30 spaced above the aperture. The free end of the pilot arm 30 rests in a notch in an upturned wall 31 integral with the tubular clamping member 18. A coiled spring 32 mounted on the pilot arm 30 between the wall 31 and the end of the pilot arm integral with the slide 23 exerts a constant force against the slide to urge the slide towards closed position. The slide 23 is provided with a pair of flanges 33 spaced from the top wall of the tubular clamping member 18. The tubular clamping member 18 has a flat spring 34 secured to the underside of its top wall in any suitable manner. The spring 34 has a tongue 35 adapted to overlie the aperture 27 and a pair of detents 36 adapted to engage against the edges of the flanges 33 when the slide 23 is moved to open position to hold the slide in open position as shown in Figure 2. The slide 23 will remain in open position as long as the top cover member is separated from the head 14 of the binding member. As soon as the head 14 is inserted through the aperture 27 it engages the tongue 35 and moves the detents 36 from holding position. Movement of the detents from holding position causes the spring 32 to automatically move the slide to closed position.
- 55 It will be seen that I have provided a loose leaf binder in which the top cover member may be locked against removal or may be retained securely in place while being readily removable.
- 60 During the day while the binder is being referred to frequently, the binding members 10 may be kept slightly loosened, and the top cover member may be removed by moving the slide 23 and may be securely attached to the binding members by simply snapping the top cover member over the heads 14 of the binding members. When it is desirable to prevent removal of the top cover member it is necessary only to tighten the binding members 10 against the contents of the binder.
- 75 In the embodiment illustrated in Figure 4, the

bottom cover member includes a cover 37 and a tubular clamping member 38 hingedly connected thereto in any suitable manner. The ends of the tubular clamping member are closed by means of a pair of end caps 39. The top wall 5 of the tubular clamping member is apertured, as indicated at 40. A stud 41 is secured to the bottom wall of the tubular clamping member in any suitable manner and projects through the aperture 40. The stud 41 is threaded, as indicated at 10 42, to receive an internally threaded rigid binding member 43.

The binding member 43 is provided with a head 44 and a restricted neck portion similar to the head 14 and neck 15 of the flexible binding member of Figures 1-3. The sheet holding portion of the binding member 43 is of uniform cross sectional area. The lower portion of the binding member may be threaded downwardly until it abuts the bottom wall of the tubular clamping member. This structure allows for adjustment equal to the thickness of the tubular clamping member 38 while maintaining the uniform cross sectional area of the sheet holding portion of the binding member.

In view of the fact that the binding member 43 cannot be tightened against the contents in the same manner as the flexible binding member 10, it is not possible to lock the top cover member against removal as in the case of the embodiment illustrated in Figures 1-3. Accordingly, the flanges 28 are omitted from the slide in the top clamping member. Otherwise the structure of the top cover member is an exact duplicate of the structure of the top cover member illustrated in Figure 1. The various parts of the top cover member in Figure 3 are designated by the same reference numerals used to designate the same parts in Figure 1. It is not deemed to be necessary to repeat the detailed description of this 40 structure.

Although I have described two embodiments of my invention in detail, it will be understood that the description thereof is illustrative rather than restrictive, as many details may be modified or changed without departing from the spirit or scope of my invention. Accordingly, I do not desire to be restricted to the exact construction described, except as limited by the appended claims.

I claim:

1. In a loose leaf binder, a pair of cover members, a plurality of binding members secured to one of said cover members, means to tighten said binding members against the contents of the binder, a slidable locking member in said other cover member, means adapted to actuate said slidable locking member automatically upon engagement of said second mentioned cover member with said binding members to lock said second mentioned cover member to said binding members, and means to prevent movement of said slidable locking member to open position when said binding members are held tightly against the contents of the binder.
2. In a loose leaf binder, a pair of cover members, a plurality of binding members secured to one of said cover members, a slide positioned within said other cover member, said slide being adapted to engage said binding members to lock said cover members against separation, means for moving said slide to open position to permit disengagement of said second mentioned cover member from said binding members, and a spring detent for holding said slide in open position.

3. In a loose leaf binder, a cover member, a plurality of headed binding members secured to said cover member, a second cover member, a 5 slideable locking member positioned in said second cover member and adapted to engage said headed binding members, and means to hold said locking member in open position while said second cover member is disengaged from said headed binding members, said means being released upon engagement of said second cover member with one of said headed binding members.
4. In a loose leaf binder, a pair of cover members, a plurality of binding members secured to one of said cover members, a slide positioned within said other cover member, said slide being adapted to engage said binding members to lock said second mentioned cover member against separation from said binding members, means for moving said slide to open position to permit disengagement of said second mentioned cover member from said binding members, and means for holding said slide in open position, said last mentioned means being moved from holding position upon engagement of said binding members with said second mentioned cover member.
5. In a loose leaf binder, a pair of cover members, a plurality of binding members secured to one of said cover members, means to tighten said binding members against the contents of the binder, slideable locking means positioned in said other cover member, means to move said locking means to open position, a detent to hold said locking means in open position, one of said binding members being adapted to disengage said detent when said second mentioned cover member is engaged with said binding members, and means to prevent movement of said locking means to open position when said binding members are held tightly against the contents.
6. In a loose leaf binder, a pair of tubular clamping members, a binding member secured to one of said clamping members, said binding member having a head at its free end and a restricted neck portion adjacent said head, a slide in said other clamping member having a keyhole shaped aperture, the large portion of which is adapted to receive said head, and the restricted portion of which is adapted to engage the restricted neck portion of said binding member after said head has been inserted in said aperture, a projection on said slide lying between 5 said binding member and the large portion of said keyhole aperture when the binding member is engaged by the restricted portion of said aperture, and means to force said head against said slide so that opening movement of said slide is 10 prevented by said projection.
7. In a loose leaf binder, a binding member adapted to project above the contents of the binder, a cover member having an aperture in which the uppermost portion of said binding member is adapted to be positioned, a slideable locking member in said cover, and means to hold said locking member in open position, said binding member being adapted to move said last mentioned means from holding position when its 15 uppermost portion is inserted in said cover.
8. In a loose leaf binder, a headed binding member projecting above the contents of the binder, a cover member in which the head of said binding member is adapted to be positioned, a locking 20 member in said cover, means to hold said locking member in open position, said holding means being released by said binding member when said head is positioned in said cover, and means for automatically moving said locking member into 25 locking engagement with said binding member when said holding means is released.
9. In a loose leaf binder, a pair of cover members, a plurality of binding members secured to one of said cover members, a slide positioned 30 within said other cover member, said slide being engageable with said binding members to lock said cover members against separation, spring means for normally urging said slide toward locking position, and means to hold said slide in 35 open position against the action of said spring, one of said binding members being adapted to engage said last mentioned means to release it from holding position when said second mentioned cover is positioned on said binding member. 40 45

PAUL O. UNGER.
